FENDER TOOL

Carl William Meinhardt, Fargo, N. Dak.

Application May 5, 1938, Serial No. 206,260

1 Claim. (Cl. 81—15)

The present invention relates to new and useful improvements in fender tools for use particularly in automobile repair shops or garages and has for its primary object to provide, in a manner as hereinafter set forth, a device of this character embodying novel means for pulling out or straightening vehicle fenders which have been bent.

Another very important object of the invention is to provide a tool of the aforementioned character which may also be used for straightening other portions of the vehicle, such as body panels, doors, radiator grills, etc.

Still another very important object of the invention is to provide a tool of the character described embodying a novel construction and arrangement whereby said tool may be expeditiously adjusted to meet various conditions.

Other objects of the invention are to provide an automobile repairing tool of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference 0 designate corresponding parts throughout the several views, and wherein:

Figure 1 is a plan view of an embodiment of the invention, showing an application of the device to an automobile fender.

Figure 2 is a cross sectional view through the tool and a portion of a fender.

Figure 3 is a sectional view, taken substantially on the line 3—3 of Fig. 1.

Figure 4 is a plan view of the device.

Figure 5 is a perspective view of the base.

Figure 6 is a detail view in elevation of the element which is used for straightening radiator grills.

Figure 7 is a detail view in elevation of the element which is used for pulling out bent or dented body panels, doors, etc.

Figure 8 is a detail view in perspective, showing an end portion of the lever and the head which is mounted thereon.

Referring now to the drawings in detail, it will be seen that the embodiment of the invention which has been illustrated comprises a base which is designated generally by the reference numeral 1. The base 1 includes a substantially rectangular metallic plate 2 having mounted on

one side thereof a cushion or pad 3 of suitable material, preferably sponge rubber.

Rotatably mounted on the other side of the plate 2 is a substantially U-shaped metallic bracket 4. Rotatably mounted in the substantially U-shaped bracket 4 is a ring 5. Trunnions 6 project from diametrically opposite sides of the ring 5, said trunnions being journaled in the bracket 4 for rotatably supporting said ring therein. This is illustrated to advantage in Fig. 10 3 of the drawings.

Slidably mounted in the ring 5 is a metallic hand lever 7 of suitable length and diameter. Heads 8 are provided on the ends of the lever 7. Slidably mounted on the lever 7 is a link or loop 15 9. The reference numeral 10 designates a multiple hook which is swivelly mounted on the loop 9. It will be observed that one of the bills 11 is on the free end of the shank of the hook 10 and that the other bill 12 projects from said 20 shank at an intermediate point.

It is thought that the operation of the tool will be readily apparent from a consideration of the foregoing. When the skirt or marginal portion of a fender, as at 13, is to be pulled out after it has been bent, the padded or cushioned base 1 is engaged with the crown of said fender and one of the bills 11 or 12 of the hook 10 is engaged with the edge of the skirt portion of said fender, substantially as illustrated in Fig. 1 of 30 the drawings, for example. Then, by pulling the outer or free end of the lever 7 in the proper direction the bent portion of the fender may be expeditiously pulled out or straightened. The 25 slidable mounting of the hook 10 on the lever 7, the slidable engagement of said lever 7 in the ring 5, the rotary mounting of said ring 5 in the bracket 4 plus the rotary mounting of said bracket 4 on the base 1 permit the tool to be readily adjusted in a manner to meet substantially all conditions as well as to vary the lever- 40 age of the handle or member 7. Also, for certain fender work, the base 1 may be slid to an intermediate point on the lever 7 and the hook 10 may be mounted on the forward end portion 45 of said lever 7. With this arrangement of the members 1 and 10 the free or outer end portion of the lever 7 is pushed toward the fender, rather than pulled away from said fender. The swivel mounting of the hook 10 on the loop 9 permits 50 either of the bills 11 or 12 to be readily used.

In Figure 6 of the drawings, the reference numeral 14 designates a single hook which is adapted to be used for straightening the bars or fins of radiator grills. The hook 14 is swivelly 55

mounted in a loop 15 which is adapted to be slidably mounted on the lever 7.

Referring now to Fig. 7 of the drawings, it will be seen that the reference numeral 16 designates a metallic rod which may be used for pulling out dents in body panels and doors. On one end, the rod 16 is provided with a substantially triangular eye or loop 17 which is adapted to receive the hook 10 for slidably mounting the rod 16 on the lever 7. A substantially flat head or enlargement 18, which is adapted to be soldered to the work, is provided on the other end of the rod 16. After the dent has been pulled out of the panel the rod 16 is removed from said panel by simply breaking the solder joint.

It is thought that the many advantages of a tool constructed in accordance with the present invention will be readily understood and although a preferred embodiment of the device is

as illustrated and described, it is to be understood that changes in the details of construction and in the combination and arrangement of parts may be resorted to which will fall within the scope of the invention as claimed.

What is claimed is:

A tool of the class described comprising a base engageable with the work, said base including a metallic plate, a cushion on one side of said plate, a substantially U-shaped bracket rotatably mounted on the other side of the plate, a ring pivotally mounted in the bracket and including trunnions journaled in said bracket, a hand lever slidably mounted in the ring, a loop slidably mounted on said hand lever, and a hook swivelly mounted on said loop, said hook being engageable with the work for operatively connecting the lever thereto.

CARL WILLIAM MEINHARDT.
